UNITED STATES PATENT OFFICE.

CARL G. PFEIFFER, OF PEEKSKILL, NEW YORK.

DRYING MACHINE.

Application filed June 12, 1920. Serial No. 388,479.

To all whom it may concern:

Be it known that I, CARL G. PFEIFFER, citizen of the United States, and resident of Peekskill, in the county of Westchester 5 and State of New York, have invented a certain new and useful Drying Machine, of which the following is a specification.

This invention relates to the making of beads and has for its object the provision 10 of means for drying the lacquers that are applied to the articles during the processes of manufacture. The object is attained by the means set forth in this specification. The formed bead, of glass or other material, is treated to successive coats of lacquers, each coating having to be dried 15 before the application of another coating. It is important that the drying be accomplished without the coating running off or 20 gathering to one side of the bead, as it is naturally inclined to do. Accordingly the means to be described are designed to effect a uniform distribution of the lacquers all over the bead during the process of drying, 25 which consists in keeping the bead in constant rotation and motion until the drying is complete.

Referring to the accompanying drawings, Fig. 1 is a plan of the drying machine. Fig. 30 2 is a side elevation of the machine. Fig. 3 is an elevation of the left hand end of the machine. Fig. 4 is a transverse section of the machine through the lines B in Figs. 1 and 2. Figs. 5 and 6 are detail views of 35 axle parts. Fig. 7 is a transverse section through the line C, Fig. 1. Fig. 8 is a plan of the pads on which the beads are carried. Fig. 9 is an explanatory detail of the adjustable end of the upper guide frame. Fig. 40 10 is an explanatory detail of the adjustable end of the track for the pads.

Figs. 1 and 2 show the end of a structure that is in practice about twenty feet long between the parts of the figures, the 45 parts omitted being precisely a continuation of the inner end portions of the two figures that are shown in transverse section in Fig. 4. The drawings are upon a scale of one-eighth of the actual size. The machine is mounted upon a table, 1, any convenient elevation from the floor, and comprises a horizontally moving belt, pad axles attached to the belt, pads for holding the beads the pads carried on said axles, a track 50 in which the pads travel, and stop guiding frame for the pads.

Flanged pulleys are supported horizontally in standards 7 and 3, Figs. 2, 3 and 4. The pulley α is rotated by means of a worm gear wheel 23 and pinion 24, Figs. 60 1, 2 and 3, the pinion driven by a pulley 25 and belt 26, Figs. 1 2 3. A leather belt b connects the two pulleys α and α' . Upon the belt at suitable intervals are pad axles, shown in enlarged detail in Figs. 5 and 6. 65 It comprises two parts, a slotted part or hub c that has a flange c'' perforated as at c''' for belt rivets, by means of which it is fastened to the belt, and the axle part e that has a flattened head c^2 fitted to the slot 70 in the hub. A rivet c^1 constitutes a pivot on which the axle swings upwards, as in Figs. 7 and 3, but is held normally in a horizontal position by the square shoulder c^3 , the upper corner of the head being 75 chamfered to a radius with the pivot.

A frame work is erected around the pulleys and the belt. The beads to be handled are placed on the ends of wires, and the wires are set in holes in a circular 80 block or pad, a plan of which is given in Fig. 8. It is a plain circular block of wood, a half to three-quarters of an inch in thickness, with a hole 12 in the center to receive the axle e , and is made usually to hold about 85 one hundred pins, the pins insertible in small holes in the block, as in Figs. 7 and 8. A pad A is shown in place in the machine in Fig. 4. The pads are placed on the axles 90 e and are carried along by the belt, the positions of the pads in relation to the frame work being shown at A, Fig. 4, and by broken lines to avoid confusion, in Figs. 2 and 3, and at the moment of discharge from the machine in Fig. 7. 95

The pads travel in a track provided in the frame f that is supported on the table 1 by stands 2, 4, and r' , shown particularly in Figs. 2 and 4. The frame is constructed to form a groove or track i , Figs. 1, 2, 3, 4 and 10, that follows the contour of the belt and pulleys to near the end of the track, and at such a distance below the axles on the belt as to cause the pads to roll on the track thus afforded. To offer a frictional 100 resistance to the periphery of the pads to prevent their sliding instead of rolling or revolving, the bottom of the track is covered with rubber belting, i' , Figs. 2, 4 and 10.

To afford support and steadiness for the 110 long belt it is enclosed within a grooved frame b' , Figs. 1, 2, 3 and 4, enclosing the

belt except an opening in front to admit of the passage of the axle hubs *a*. This frame is supported upon extensions *u* of the standards 4, Fig. 4.

5 A frame *g g'* is supported above the belt frame by brackets *m* attached to the standards 4, Figs. 1, 2, 3 and 4, a distance above the lower track enough higher than the diameter of the pads to prevent contact with 10 the periphery of the pads. This frame, seen in cross-section in Fig. 4, is made in two parts, the outer part wider than the inner to afford the flange *g'*, Figs. 3 and 4, which constitutes a guide for the tops of the pads 15 in their travel. No flange is needed behind the pads as the hub of the axle will prevent the pads leaning too far in that direction. The pads are placed on the axles and in the track at the left hand end of the machine, 20 at *i'*, Figs. 1, 2 and 3.

On the opposite side, at the same end of the machine, the pad track and upper guide assume forms that automatically discharge the pads from the machine. A brace *h*, Figs. 25 1, 2 and 3, attached to the guide *b'* at *d*, and to the post *r* rigidly maintains those points in proper relational distances. The guide *g*, at the point 41 merges into a crooked arm *l* that is attached at its forward end to the 30 post *r*, and to the guide *g* at the point 42.

The track frame *f* from the point 40, Fig. 1, widens and assumes an angularity as if its inner edge were twisted upwards towards and to meet the pad axles, and gradually 35 elevated to its terminal, as shown in Figs. 1, 3 and 7. The outside guide *j* recedes to a larger radius somewhat eccentric to the pulley *a*, diverging as it approaches the end of the machine, and gradually sloping upwards, as at *i''*, Fig. 3. The inner edge 43 of the track also gradually rises so that the pad axles impinge against it and are lifted by it. As the pad reaches the diverging guide at the point 40 the flange *n* on the 40 arm *l*, see Fig. 3, causes the pad to lean inwardly, and the combined effects of the drawing-in flange *n*, the diverging and sloping guide *j* and the sloping path *i'*, with the lifting of the axle *e*, brings the pad into the 45 position shown in Fig. 7, where the axle separates from the pad, the pad slides down on the chute *v*, Fig. 3, and the axle drops from the track point 14 and assumes its normal position as shown in broken lines in *e'*. The end of the sloping track is secured to the 50 post *r r'*, as at *i''*.

A running belt, particularly of a narrowness and length of the one employed, is liable to stretch, so that provision is made for 55 taking up belt slackness, and to adjust the frame accordingly. The pulley *a'* has its bearing in the standard 3, and as shown particularly in Figs. 2 and 9, the standard is adjustable in the direction of the length of 60 the table, by means of the slots 8 in the base

of the standard and the fastening bolt 8'.

The guide frame *g* is extensible at the pulley *a'* end by these adjustable parts: The frame is made of two strips, *g g'*, Fig. 4, that are particularly set forth in Fig. 9, the parts being numbered for clearness of the details. The segment 22 has extensions 19 and the flange *g'* on the segment can be integral with the body of the segment. The inner rail 17 of the frame in the figure has 75 the flange *g'* added to it by the wider strip 16, secured to the rail 17. The segment end is held between the strips 16, and is secured to them by means of the bolts 20 21. As shown in Fig. 2, slots *s* through the strip 80 admit of the extension of the segment as in Fig. 9. The ends of the strips as extended at 18 and the finish of the corners *p* are for the purpose of symmetry in the construction. 85

The corresponding ends of the track frame *f* supported on standards 2, Fig. 2, are separable and extensible like the upper frame, as in Fig. 10 by means of slots 25 in the standards, shown in broken lines, 90 slideable on the fastening bolts 24, Fig. 2. The rubber track *i''* can be made to bridge the space by the insertion of a piece of rubber as at 26, if the space becomes great enough to require it. 95

This machine is used in a warm room free from dust. The pads, filled with beads to be dried placed in the machine are kept in constant motion and rotation and the object sought is admirably accomplished. The 100 simple rotation of the pads would not be so effective as the double motion given to them which moves them through a constantly changing atmosphere, whereas simply rotating the pads tends to create only an eddying current of air within narrow limits, being less effective, and the beads near the center of the pad deriving little benefit therefrom. 105

Having described the invention, what I 110 claim and desire to secure by Letters Patent, is—

1. In a driving machine the combination of a table, pulley shaft standards near the ends of the table, pulley bearings on said standard, horizontal pulleys, supported in said bearings, means for driving one of the pulleys, a belt carried by the pulleys edge-wise with relation to the table, a grooved 115 guide-path adjacent to the lower edge of the belt from a given starting point to a point of delivery, a grooved guide above the top edge of the said belt parallelling the path below the belt to near the point of delivery, hinged pad carriers on the belt, the outer flange of the guide-path near the point of delivery diverging from the belt the inner edge of said guide-path gradually 120 diverging and rising to form a sloping surface to the outer flange, and to engage with the 125 inner edge of the outer flange of the guide-path, 130

hinged carrier to elevate the carrier from its horizontal course, the upper guide converging towards the pulley in correspondence with the divergence of the guide-path, and a 5 sudden break in said elevation to cause the dropping of the carrier to normal.

2. In combination with drying pads, pivoted axles for supporting and carrying the pads, the axles attached to an endless belt 10 driven upon horizontal pulleys, means for driving one of the pulleys, a guide-path below the belt in which the pads travel, the traversing causing the pads to revolve, a groove above the belt as a guide to the top of 15 the pads, the guide-path diverging and the upper guide converging near the point of delivery, the guide-path merging into an inclined plane, the inner edge of the plane lifting the carrier to separate it from the 20 pad.
3. In a drying machine as described, embodying an endless horizontal belt, pad carriers on the belt, a guide-path and a guide adjacent to the belt to guide and to cause 25 a rolling of the pads, the guide-path widening and diverging from the belt near the point of pad delivery, the inner edge of the guide-path gradually rising to meet and lift the carrier axle and to form a sloping 30 surface to draw the pad from its carrier.
4. The combination in a drying machine as described, embodying an endless horizontal belt, pad carriers on the belt, a guide and a guide-path adjacent to the belt to

guide and cause a rolling of the pad, of the 35 guide-path widening and diverging near the point of pad delivery, the upper guide converging towards the belt in correspondence with the diverging of the guide-path, the inner end of the guide-path gradually rising 40 to meet and lift the carrier axle and to form a sloping surface to the outer flange of the guide-path.

5. In a drying machine as described, means for carrying the drier pads comprising 45 a slotted hub, a base to the hub for attachment to the carrier belt, an axle, a hub on the axle to fit in the slot in the hub, a pivot through the hub and the axle head, the upper corner of the axle head chamfered away to a radius with the pivot. 50

6. In a drying machine as described, embodying an endless horizontal belt driven upon horizontal pulleys, with guides above and below the belt, means for tightening the 55 belt and adapting the guides thereto, comprising slots in the base of the forward pulley whereby the base is slidable upon its foundation, and extensible means upon the top guide comprising a separable half-circular end of the frame with arms extended tangentially with the frame, with flange parts on the main frame extended to embrace 60 said arms, slots through the said arms and extensions, and fastening bolts through the 65 slots.

CARL G. PFEIFFER.
